DESIGN FOR A STEERING WHEEL SPINNER KNOB

Joel R. Thorp, West Allis, Wis., assignor to The Fulton Company, West Allis, Wis., a corporation of Wisconsin

Application November 27, 1944, Serial No. 116,578

Term of patent 7 years

(Cl. D14—30)

To all whom it may concern:

Be it known that I, Joel R. Thorp, a citizen of the United States of America, residing at West Allis, in the county of Milwaukee and State of Wisconsin, have invented a new, original, and ornamental Design for a Steering Wheel Spinner Knob, of which the following is a specification, reference being had to the accompanying drawing, forming a part thereof.

In the drawing:

Fig. 1 is a front elevational view of a steering wheel spinner knob of the present design;

Fig. 2 is a top view of the steering wheel spinner knob; and

Fig. 3 is a side view of the steering wheel spinner knob.

I claim:

The ornamental design for a steering wheel spinner knob, substantially as shown.

JOEL R. THORP.
